E. E. FORD.
NON-REFILLABLE BOTTLE.
APPLICATION FILED JULY 22, 1915.

Patented June 20, 1916.

UNITED STATES PATENT OFFICE.

ELIOT E. FORD, OF NEWARK, NEW JERSEY.

NON-REFILLABLE BOTTLE.

1,187,722.

Specification of Letters Patent. Patented June 20, 1916.

Application filed July 22, 1915. Serial No. 41,233.

To all whom it may concern:

Be it known that I, ELIOT E. FORD, a citizen of the United States, residing in the city of Newark, in the county of Essex and 5 State of New Jersey, have invented certain new and useful Improvements in Non-Refillable Bottles, of which the following is a full, clear, and exact description, such as will enable others skilled in the art to which 10 it pertains to make, construct, and use the same, reference being had to the accompanying drawings, and to numerals of reference marked thereon, forming a part of this specification.

15 My invention relates to an improvement in non-refillable bottles, and the object thereof is to provide a bottle which having been emptied, cannot again be refilled.

The purpose of the invention is to provide 20 a simple and inexpensive device, secured in the neck of a bottle, which will permit the contents of a bottle to be freely and readily emptied, but which will effectually prevent the bottle from being refilled, so that the 25 bottle cannot be offered a second time as an original package.

The peculiar construction of the several 30 parts are such as to effectually prevent tampering therewith, for the purpose of lifting the valve or otherwise permitting of the introduction of a liquid of any kind to replace that which has already been withdrawn from the bottle.

The invention consists in the novel construction and combination of the several 35 parts, as will be hereinafter fully set forth and pointed out in the claims, reference being had to the accompanying drawings forming a part of this specification, in which 40 similar characters of reference indicate corresponding parts in all of the figures.

Figure 1 represents a vertical section of the preferred form of my device, in place in a bottle neck. Fig. 2 represents a similar 45 view showing the device in an inclined position. Figs. 3, 4, 5 and 6 represent respectively, on an enlarged scale, transverse sections taken on lines $x-x$, $y-y$, $z-z$ and $a-a$ of Fig. 1 respectively, and looking in 50 the direction indicated by the arrow.

The device proper consists of a cylindrical shell or casing 1, which may be held in the neck 2 of the bottle by frictional contact or by means of a cork packing or the like 3, or by means of a shell being provided with a circumferential groove 4 formed therein by spinning

or forcing the metal of the shell outwardly into intimate engagement with the packing, which may be done by suitable tools, or in any other convenient or desired manner. 60 The upper edge of the shell or casing is preferably provided with a flaring opening 5, of a configuration corresponding with that of the mouth of a bottle. Fitted into or made integral with the lower end of the shell 1 is a valve seat 6, as clearly indicated in Figs. 1 and 2 of the drawings, said valve seat 6 being provided with suitable openings, and a tubular extension 7 having a flange 8. A spring-actuated valve 9, comprising a disk 10 of smaller diameter than the inside diameter of the shell or casing 1, is by means of the valve stem 11, slidably secured in the tubular extension 7. 70

12 represents a head formed on the end 75 of the valve stem 11, and interposed between the inner side of said head and the outer side of the flange 8 of the extension 7 is a spiral spring 13, designed to keep the inside of the valve disk 10 in contact with 80 the inner or upper side of the valve seat 6, so as to form a closure when the device is in the position as indicated in Fig. 1 of the drawings.

A rotatable member 14, provided with a 85 weighted extension 15, is rotatably mounted upon the tubular extension 7 of the valve seat 6, and pivotally secured to said extension is a float-supporting element 16, the free end of which carries in any convenient 90 or desired manner a float 17.

A vane or centering element 18 is pivotally secured to the float-carrying member 16 in any desired or convenient manner, and of a dimension corresponding approximately with the dimension of the inside diameter of the neck of the bottle, as clearly indicated in Fig. 1 of the drawings, said vane serving the purpose of keeping the movable parts of the device below the casing 1, in the position indicated in Fig. 1 of the drawings, and is only moved out of that position into the position indicated in Fig. 2 of the drawings, by the flow of the fluid when the bottle is tilted preparatory to removing some of the contents thereof, in which case, the lower part of the vane 18 which is designated by the numeral 19, is received into a cut-away portion 20 of the float 17. 100

The vane 18 and its position on the float-carrying element serves to steady the parts 110

of the device in the neck of the bottle, and to prevent the same from being injured by being brought into forcible contact with the inside of the neck of the bottle by careless manipulation of the bottle.

The cylindrical shell or casing 1 is provided with an inwardly-extending annular flange 21, which may be an integral part of said shell, or may be in the nature of an annular ring secured to the interior of the shell in any desired or convenient manner. A short distance above said shell 1, a baffle-plate or disk 22, the outside diameter of which is a trifle larger than the inside diameter of the said flange 21, is preferably, frictionally secured to the interior of said shell by means of three integral extensions 23, formed on said disk 22. This baffle-plate or disk 22, together with the inwardly-extending annular flange 21, provide means whereby the tampering with and manipulation of the valve disk 10 from the exterior of the bottle is reduced to a minimum.

It will be understood that the valve disk 10 is made of such a diameter that it will properly seat itself upon the valve seat 6, and when so seated, will cover the openings in said valve seat and kept so seated by the spiral spring 13.

Any approved material may be employed in the construction of the various parts; ordinarily, however, they are made of metal, with the exception of the float, which is preferably made of cork.

In the operation of the device, when the bottle is in an upright position, the under side of the valve disk 10 will rest upon the upper surface of the valve seat 6 and cover the openings therein, thus preventing the liquid that may be poured in the top of the stopper passing into the bottle; and furthermore, the disk 22, together with the inwardly-extending annular flange 21, will prevent any person tampering with the valve by means of a wire or like article.

When it is desired to pour liquid from the bottle, when the bottle is inverted as shown in Fig. 2, the liquid will act upon the under side of the float 17, and the upper portion of the vane 18, causing the float to rest against the neck of the inside of the bottle, moving the lower part 19 of the vane 18 into the cut-away portion 20 of the float 17 and simultaneously causing the upper part of the vane 18 to impinge against the rectangular extension 24 of the float-carrying element 16, thus causing said extension to engage with the head 12 formed on the end of the valve stem 11, comprising the spiral spring 13, and thereby causing the valve disk 10 to uncover the openings in the valve seat 6, and the

liquid will pass through the openings in the valve seat 6 around the valve disk 10, through the annular flange 21 and through the annular opening formed between the baffle-plate or disk 22 and the shell or casing 1, from whence it will find an exit and likewise a ready exit from the bottle.

It will be observed that a stopper of this description is exceedingly economic; it is durable and practical, and may be applied to any form of bottle.

Experience has demonstrated that the organization above described is a highly efficient one, and while the device described is the preferred embodiment of my present invention, I do not wish to be limited to the exact details of construction and combination herein shown and described, as obvious modifications thereof, not involving the exercise of invention, may be made by any skilled mechanic, and such departures from what is herein shown and described, I consider within the scope and terms of my claims.

I claim:

1. In combination with a bottle, within the neck of which is fitted a shell having a valve seat formed in its lower end, said valve seat being provided with a tubular extension, an inwardly extending annular flange located between said valve seat and the upper end of said shell, a valve having a stem to operate in said tubular extension of the valve seat, a weighted member rotatably mounted upon said tubular extension, a float-supporting element pivoted to one end of said rotatable member and a baffle plate located in said shell in close proximity to said inwardly extending annular flange.

2. In combination with a bottle, within the neck of which is fitted a shell having a valve seat formed in its lower end, said valve seat being provided with a tubular extension, an inwardly extending annular flange located between said valve seat and the upper end of said shell, a spring-actuated valve having a stem to operate in said tubular extension of the valve seat, a weighted member rotatably mounted upon said tubular extension, a float-supporting element pivoted to one end of said rotatable member, a centering element pivotally secured to said float-supporting element and a baffle plate located in said shell in close proximity to said inwardly extending annular flange.

This specification signed and witnessed this 9th day of July, 1915.

ELIOT E. FORD.
